Specification for Design.

Patented Mar. 29, 1921.

Application filed August 23, 1920. Serial No. 405,512. Term of patent 14 years.

To all whom it may concern:

Be it known that I, ALPHEUS W. ALTORFER, a citizen of the United States, residing at 1516 North Perry avenue, Peoria, county of Peoria, and State of Illinois, have invented a new, original, and ornamental Design for Wringer-Frames, of which the following is a specification, reference being had to the accompanying drawing, forming part thereof.

The figures are respectively, a front top and end view of the wringer frame, showing my new design.

I claim:

The ornamental design for a wringer frame, as shown.
